G. H. DOWNS.

CAR WHEEL.

APPLICATION FILED MAR. 24, 1908.

947,435.

Patented Jan. 25, 1910.

UNITED STATES PATENT OFFICE.

GEORGE HENRY DOWNS, OF NORTH POWDER, OREGON, ASSIGNOR OF ONE-HALF TO
WILLIAM E. GRACE, OF PORTLAND, OREGON.

CAR-WHEEL.

947,435.

Specification of Letters Patent. Patented Jan. 25, 1910.

Application filed March 24, 1908. Serial No. 423,002.

To all whom it may concern:

Be it known that I, GEORGE HENRY DOWNS, a citizen of the United States, and a resident of North Powder, Union county, State of Oregon, have invented a new and useful Improvement in Car-Wheels, of which the following is a specification, reference being had to the accompanying drawings as constituting a part thereof.

10 This invention, while relating more particularly to car-wheels, also applies to vehicle-wheels in general.

It has for its object to obtain an efficient ball-bearing wheel comprising, in its broad sense, a ring-like tread, rotating upon the periphery of a circular web, non-rotatably mounted on an axle-end, sides holding the tread in place, bearing-balls interposed in an effective way between the bearing or opposed faces of the fixing and moving parts, and chambers for lubricant, all arranged as hereinafter more fully described and to accomplish the purposes set forth.

I obtain my object by the combination of 25 parts illustrated in the drawings referred to, in which,

Figure 1 is a diametric section of my improved car-wheel; Fig. 2 is a side elevation thereof with the near side plates removed so 30 as to disclose the hub-like web of my wheel; Fig. 3 is a partial elevation of one of the annular members of such side plates; Fig. 4 is an inner side view of one of the outer circular members of said side plates which 35 overlaps and closes the central opening of the annular member of said plates; and Figs. 5 and 6 are details of construction more fully explained in the body of this specification.

40 It is in the first instance to be noted that the shouldered-end of the axle a , corresponding to the usual journal end of a common car-axle, is made square in cross section, because my wheel is so constructed that the 45 hub of the wheel does not rotate, but instead thereof the rim or ring-like tread, m , of the wheel rotates upon the hub. The web-like hub, b , of my wheel is provided on its rim with a groove in which to receive bearing-balls c . To admit of the insertion of the 50 bearing-balls, c , the web, b , is made with an opening, d , closed by a piece d' , of which details are shown in Figs. 5 and 6. On either side of the web, and spaced therefrom, are 55 circular side plates k , k' , and between such

outer circular plates and the web are annular side plates g , g' , the rims of the latter projecting beyond the periphery of the web. The outer faces of the web b are respectively made with annular grooves e , concentric 60 with the axis of the wheel, in which to receive bearing-balls f , and the inner faces of the annular side plates g , g' are likewise made with annular grooves, corresponding with the grooves e , in which to 65 receive said bearing-balls f . Said annular side plates g , g' are further provided on their outer faces with annular grooves in which to receive bearing-balls h . The outer circular side plates k , k' overlap the inner 70 edges of the annular side plates g , g' and they are made with corresponding grooves on their inner faces for said bearing-balls h . The annular side plates g , g' are made with sloping portions i and shoulders j , leaving 75 recesses on their outer faces, in which are seated the rims of the circular side plates k , k' . The cut-away central portions l of the annular side plates g , g' are spaced from the axle-end a' , while the eye of the web b 80 is made square, so as to be rigidly mounted on such axle-end a' . The circular side plates k , k' are also made with rectangular eyes k^2 , so as to be rigidly mounted on the 85 axle-end a' .

Encompassing the rim of the web b between the annular side plates g , g' in the ring-like tread m , made with the usual flange m' and shoulders n , n' , in which to receive the rims of said annular side plates g , g' , 90 as shown in the sectional Fig. 1. The ring-like tread m is bolted by bolts o between the rims of said annular side plates g , g' . It is preferable to introduce some packing strips at p , p' , q , q' , to keep out dust. The extremity of the axle-end a' is threaded so as to receive nuts r , r' , an intermediate washer s , and a cotter-pin t , or like contrivances, to securely hold the wheel in place. The manner of assembling the parts of my wheel 95 is self evident from the foregoing description, and particularly from the diametric section thereof shown in Fig. 1.

Before putting on the outer one of the circular outer side plates k , k' , the cavities provided by the cut-out portions l is filled with lubricant, which, passing along the crevices u , u' , reaches the grooves of the bearing-balls c , f , h . It is preferable to fill 105 said cavity l about half full with lubricant, 110

and this will provide ample lubrication for a considerable length of time, though the car provided with my wheels be in continuous use.

5 I claim:

1. In combination with an axle-end, a wheel comprising a circular web non-rotatably mounted on the axle-end, outer circular side plates also non-rotatably mounted 10 on the axle-end on either side of the web and laterally spaced therefrom, annular side plates between the web and the circular side plates, the central portions of the annular side plates being cut away so as to be spaced 15 from the axle-end and thus provide chambers for lubricant, the rims of the annular side plates projecting beyond the periphery of the web, and the rims of the circular side plates overlapping the inner edge of said 20 annular side plates, a ring-like tread rotatably mounted on the periphery of the web between the projecting rims of the annular side plates, bearing balls between the opposed faces of the side plates and the periphery of the web and said rim-like tread, and means securing the wheel on the axle-end.

2. In combination with an axle-end, a wheel comprising a circular web non-rotatably mounted on the axle-end, outer circular side plates also non-rotatably mounted 30 on the axle-end on either side of the web and laterally spaced therefrom, annular side plates between the web and the circular side plates, the central portions of the annular side plates being cut away so as to be spaced 35 from the axle-end and thus provide chambers for lubricant, the rims of the annular side plates projecting beyond the periphery of the web, and the rims of the circular side plates overlapping the inner edge of said annular side plates, a ring-like tread rotatably mounted on the periphery of the web between the projecting 40 rims of the annular side plates, bearing balls between the opposed faces of the side plates and the periphery of the web and said rim-like tread, and means securing the wheel on the axle-end.

3. In combination with an axle-end, a wheel comprising a circular web non-rotatably mounted on the axle-end, outer circular side plates also non-rotatably mounted 55 on the axle-end on either side of the web and laterally spaced therefrom, annular side plates between the web and the circular side plates, the central portions of the annular side plates being cut away so as to be spaced 60 from the axle-end and thus provide chambers for lubricant, the rims of the annular side plates projecting beyond the periphery of the web, and the rims of the circular side plates overlapping the inner edge of said annular side plates, a ring-like tread rotatably mounted on the periphery of the web between the projecting 65 rims of the annular side plates, bearing balls between the opposed faces of the side plates and the periphery of the web and said rim-like tread, and means securing the wheel on the axle-end.

formed with annular recesses near their inner edges, and the rims of the circular side plates overlapping and setting in such recesses, a ring-like tread rotatably mounted on the periphery of the web between the 70 projecting rims of the annular side plates, bearing balls between the opposed faces of the side plates and the periphery of the web and said rim-like tread, and means securing the wheel on the axle-end.

4. In combination with an axle-end, a wheel comprising a circular web non-rotatably mounted on the axle-end, outer circular side plates also non-rotatably mounted 75 on the axle-end on either side of the web and laterally spaced therefrom, annular side plates between the web and the circular side plates, said annular side plates being rigidly secured to the rim of the web, the central portions of the annular side plates being cut 80 away so as to be spaced from the axle-end and thus provide chambers for lubricant, the rims of the annular side plates projecting beyond the periphery of the web, and the rims of the circular side plates overlapping 85 the inner edge of said annular side plates, a ring-like tread rotatably mounted on the periphery of the web between the projecting rims of the annular side plates, bearing balls between the opposed faces of the side plates 90 and the periphery of the web and said rim-like tread, and means securing the wheel on the axle-end.

5. In combination with an axle-end, a wheel comprising a circular web non-rotatably mounted on the axle-end, outer circular side plates also non-rotatably mounted 95 on the axle-end on either side of the web and laterally spaced therefrom, annular side plates between the web and the circular side plates, said annular side plates being rigidly secured to the rim of the web, the central portions of the annular side plates being cut 100 away so as to be spaced from the axle-end and thus provide chambers for lubricant, the rims of the annular side plates projecting beyond the periphery of the web, and the rims of the circular side plates overlapping 105 the inner edge of said annular side plates, a ring-like tread rotatably mounted on the periphery of the web between the projecting rims of the annular side plates, bearing balls between the opposed faces of the side plates 110 and the periphery of the web and said rim-like tread, and means securing the wheel on the axle-end.

6. In combination with an axle-end, a 115 wheel comprising a circular web non-rotatably mounted on the axle-end, outer circular side plates also non-rotatably mounted 120 on the axle-end on either side of the web and laterally spaced therefrom, annular side 125 plates, the central portions of the annular side plates being cut away so as to be spaced from the axle-end and thus provide chambers for lubricant, the rims of the annular side plates projecting beyond the periphery of the web, and the rims of the circular side plates overlapping the inner edge of said annular side plates, a ring-like tread rotatably mounted on the periphery of the web between the projecting 130 rims of the annular side plates, bearing balls between the opposed faces of the side plates and the periphery of the web and said rim-like tread, and means securing the wheel on the axle-end.

- plates between the web and the circular side plates, said annular side plates being rigidly secured to the rim of the web, the central portions of the annular side plates being cut 5 away so as to be spaced from the axle-end and thus provide chambers for lubricant, the rims of the annular side plates projecting beyond the periphery of the web, said annular side plates being formed with annular 10 recesses near their inner edges, and the rims of the circular side plates overlapping and setting in such recesses, a ring-like tread rotatably mounted on the periphery of the web between the projecting rims of the annular side plates, bearing balls between the opposed faces of the side plates and the periphery of the web and said rim-like tread, and means securing the wheel on the axle-end.
- 20 7. In combination with a square-shouldered axle-end, a wheel comprising a circular web non-rotatably mounted on the axle-end, outer circular side plates also non-rotatably mounted on the axle-end on either 25 side of the web and laterally spaced therefrom, annular side plates between the web and the circular side plates, the central portions of the annular side plates being cut away so as to be spaced from the axle-end 30 and thus provide chambers for lubricant, the rims of the annular side plates projecting beyond the periphery of the web, and the rims of the circular side plates overlapping the inner edge of said annular side plates, a 35 ring-like tread rotatably mounted on the periphery of the web between the projecting rims of the annular side plates, bearing balls between the opposed faces of the side plates and the periphery of the web and said rim-like tread, and nuts on the axle-end holding 40 the wheel in place.
8. In combination with a square-shouldered axle-end, a wheel comprising a circular web non-rotatably mounted on the axle-end, outer circular side plates also non-rotatably mounted on the axle-end on either 45 side of the web and laterally spaced therefrom, annular side plates between the web
- and the circular side plates, said annular side plates being rigidly secured to the rim 50 of the web, the central portions of the annular side plates being cut away so as to be spaced from the axle-end and thus provide chambers for lubricant, the rims of the annular side plates projecting beyond the 55 periphery of the web, means rotatably interlocking the rims of the outer circular side plates with the inner portions of the intermediate annular side plates, a ring-like tread rotatably mounted on the periphery 60 of the web between the projecting rims of the annular side plates, bearing balls between the opposed faces of the side plates and the periphery of the web and said rim-like tread, and nuts on the axle-end holding 65 the wheel in place.
9. In combination with a square-shouldered axle-end, a wheel comprising a circular web non-rotatably mounted on the axle-end, outer circular side plates also non-rotatably mounted on the axle-end on either 70 side of the web and laterally spaced therefrom, annular side plates between the web and the circular side plates, said annular plates being rigidly secured to the rim of 75 the web, the central portions of the annular side plates being cut away so as to be spaced from the axle-end and thus provide chambers for lubricant, the rims of the annular side plates projecting beyond the periphery 80 of the web, said annular side plates being formed with annular recesses near their inner edges, and the rims of the circular side plates overlapping and setting in such recesses, a ring-like tread rotatably mounted 85 on the periphery of the web between the projecting rims of the annular side plates, bearing balls between the opposed faces of the side plates and the periphery of the web and said rim-like tread, and nuts on the 90 axle-end holding the wheel in place.

GEORGE HENRY DOWNS.
